UNITED STATES PATENT OFFICE.

LOUIS LA VECK, OF BROOKLYN, NEW YORK, ASSIGNOR TO SIMPLEX PAPER ACCESSORIES CO., INC., OF BROOKLYN, NEW YORK, A CORPORATION OF NEW YORK.

COUNTING APPARATUS.

Application filed November 12, 1921. Serial No. 514,461.

To all whom it may concern:

Be it known that I, LOUIS LA VECK, a citizen of the United States, and resident of Brooklyn, county of Kings, city and State of New York, have invented certain new and useful Improvements in Counting Apparatus, of which the following is a specification.

My invention relates to counting apparatus and has for its object to provide a simple and novel construction adapted especially for operative combination with a paper cutting machine. A further object of the invention is to construct the apparatus in such a manner that the cut sheets of paper may be accurately and dependably counted in so-called reams regardless of the number of sheets constituting the ream. Another object of the invention resides in the provision of a construction arranged to effect a count of units each consisting of a plurality of sheets. My invention further contemplates the provision of an apparatus whereby not only the sheets individually and in units comprising a plurality of sheets, but the number of reams may be counted and which is capable of being easily and quickly adjusted at any time, either while at rest or during operation, to count in accordance with the number of rolls of paper being fed to the cutter. Still another object of my invention is to provide a simple and efficient means whereby the cutting machine will be automatically stopped when a predetermined total in the count has been reached. Other more specific objects of the invention will appear from the description hereinafter and the features of novelty will be pointed out in the appended claims.

In the accompanying drawings, which illustrate an example of the invention without defining its novelty, Figure 1 is a front elevation of the apparatus; Fig. 2 is a similar view with parts removed to show the interior construction; Fig. 3 is a sectional view on the line 3--3 of Fig. 2, and Fig. 4 is a section on the line 4--4 of Fig. 2.

As shown in the illustrated example, the apparatus comprises a casing 10 of suitable form and dimensions and having a preferably removable front plate 11 provided with circular dial openings 12 and 13 and with segmental scale openings 14 and 15; the plate 11 may be secured upon the casing

in any convenient manner, as by means of 55 screws 16 and the openings 12 and 13 are preferably closed by means of caps 17 including glass or other transparent fronts 18. The counting mechanism which, for the most part, is contained in the casing 60 10, comprises a primary counting member in the form of a wheel 19 rotatably mounted upon a stud-shaft 20 which may be fixed upon or comprise an integral part of the back plate of said casing 10; the wheel 19 is provided on its periphery with a pre-determined number of teeth 21, the illustrated example showing one hundred such teeth. The means whereby said primary counter is actuated consists of a pawl 22 70 pivoted at 23 upon one arm of a bell-crank lever 24 which is mounted to rock upon the stud-shaft 20 and the other arm of which is connected by means of a link 25 with an arm 26 carried by a shaft 27 rotatably 75 mounted in the casing 10. A second arm 26^a also mounted on said shaft 27 is connected with the machine with which the counting apparatus is operatively combined; in the present instance said arm 26^a 80 is arranged for connection, by means of a pitman 28, with the rotary cutter of a paper cutting machine of any conventional type. With this arrangement the primary counting member or wheel 19 is advanced in a 85 predetermined manner, as will be more fully set forth hereinafter, each time the rotary cutter makes a complete revolution or otherwise performs a cutting operation. To prevent unintentional return movement 90 of the primary counting member 19 during a movement of recovery of the pawl 22, a spring-controlled stop-pawl 29 pivoted at 29^a in the casing 10 may be provided. A 95 coil spring 30 bears with one end against a lug 31 on the bell-crank lever 24 and with its other end engages a projection on the pawl 22 and serves to yieldingly press the latter in a direction toward the teeth 21; the pawl 22 further is provided with a roller 100 32 which co-operates with a segment 33 in a manner to be more fully described hereinafter to predetermine the point of engagement of said pawl 22 with the teeth 21, it being understood that the arrangement is such that the pawl 22 is held out of engagement with the teeth 21 as long as the roller 32 is in engagement with

the segment 33. The latter comprises part of a member 33^a which is mounted in the casing 10 so as to be adjustable about the stud-shaft 20 as a center; a pointer 34 is operatively combined with said segment 33 and co-operates with an indicating scale 35 located in registry with the scale opening 14 so as to be visible therethrough. The pointer 34, and with it the segment 33, may be adjusted to different positions by means of a suitable handle 36 which extends exteriorly beyond the casing 10; the handle 36 is preferably provided with a locking bolt 36^a arranged to co-operate with a series 15 of notches 37 in the casing 10 to fix the pointer 34, and with it the segment 33, in an adjusted position; it will be understood that, in such case, the pointer 34 may further be provided with a pivoted operating lever 20 36^b whereby said locking bolt 36^a is moved out of said notches 37 when it is desired to adjust said handle and its associated parts to different positions. A spring 36^c located between the handle and the lever serves to 25 normally maintain the bolt 36^a in engagement with the notches 37. The scale 35 is of a type to accord with the machine with which the apparatus is combined and in the present instance includes designations 30 *a* indicating the number of webs of paper which may be concurrently passed through the cutter machine to be cut into sheets; in other words, the setting of the pointer 34 on the scale 35 indicates the number of 35 sheets being cut at each operation of the rotary cutter.

At intervals corresponding to the spaces between twenty of the teeth 21, the wheel 19 is provided with rollers 38 rotatably 40 mounted upon studs 39 projecting perpendicularly from the face of said wheel 19; the rollers 38 are adapted to successively engage a roller 40 carried on one arm of a bell-crank lever 41 mounted to rock upon a 45 stud-shaft 42 fixed upon the back plate of the casing 10. The other arm of the lever 41 is provided with a rod 43 upon which a plurality of pawls 44, 44^a, 44^b and 44^c are pivoted, said pawls co-operating, respectively, with secondary counting members 45, 45^a, 45^b and 45^c mounted to rotate together upon the stud 42. The counting members, in the form of wheels, are each of a different diameter and are provided on their periphery with teeth 46 arranged, in co-operation with the teeth 21 of the primary counter 19, to accord with the different number of sheets contained in the so-called standard reams; that is, the wheel 45 is provided with twenty-five teeth arranged for a five hundred sheet ream, the wheel 45^a with twenty-four teeth arranged for a four hundred and eighty sheet ream, the wheel 45^b with twenty teeth arranged for a four hundred sheet 50 ream and the wheel 45^c with eighteen teeth arranged for a three hundred and sixty sheet ream. The operation of this part of the apparatus will more fully appear in the description of the complete operation, which appears hereinafter. The pawls 44, 44^a, 44^b and 44^c are each of proper dimensions and construction to properly co-operate with the respective counting members and further are each under the influence of a spring 47 which, in each case, tends to swing the 55 respective pawls toward the wheels 45, 45^a, 45^b or 45^c with which they co-operate, it being understood that only one pawl is in operation at a given time and that the others, while they partake of the rocking movements of the lever 41, are held in inoperative positions with respect to the secondary counting members or wheels with which they co-operate. Any suitable means may be provided for adjusting the pawls in a manner 60 to produce the desired result; for instance, a segment 48, similar to the segment 33, may be utilized for the purpose, and in such case is adjustably mounted in the casing 10 by means of a member 48^a to move in an arc 65 having the stud 42 for a centre. On its inner face the segment 48 is provided with recesses 49, 49^a, 49^b and 49^c located at different points thereon in registry with rollers 50, upon the respective pawls 44, 44^a, 44^b and 44^c; with this arrangement, when one of the rollers is in one of the recesses, its pawl will be in engagement with its co-operating 70 counting member while all of the other rollers, being out of registry with their recesses, will ride upon the inner surface of the segment 48 and thus maintain the other pawls out of engagement with their co-operating counting member. It will be understood that the recesses are all of sufficient length 75 to permit the movement of the pawls, by the action of the bell-crank lever 41, necessary to effect a one tooth advance of the respective wheels or counting members 45, 45^a, 45^b and 45^c. The segment 48 may be adjusted 80 to its different positions by means of a pointer 51 which co-operates with an indicating scale 52 located in registry with the scale opening 15 and provided with designations *b* indicating the different standard 85 reams previously referred to. The pointer 51 preferably projects over the scale 52 so as to be visible through the opening 15; the adjustment of the pointer 51 and with it the segment 48 may be also effected through 90 the medium of a suitable handle 53 which projects outwardly beyond the casing 10. The handle 53 may also be provided with a locking means similar to that with which the handle 36 is provided, and adapted to 95 co-operate with notches 54 properly located in the casing 10 to fix the pointer 51 and with it the segment 48 in an adjusted position.

The lever 41 and with it the pawls 44, 44^a, 130

44^b and 44^c are restored to normal position by means of a spring 55, the return movement of said lever 41 being arrested by means of a stop, preferably in the form of 5 an adjustable screw 56, located at the proper point in the casing 10.

At a predetermined point the secondary counting member 45 is provided with a projection, preferably in the form of a roller 10 57, which is adapted to engage a trigger 58 carried by a shaft 59 journalled in the casing 10, said trigger carrying a metallic contact member 60; the latter is arranged to engage and connect two electric terminals 15 61, as the trigger 58 is actuated by the roller 57, and thus to close an electric circuit whereby an alarm, either in the form of a light or a bell, is operated to indicate that the counting member 45 has made one 20 complete revolution which, in the illustrated example of the invention, would indicate that one ream of paper of a given number of sheets had passed through the paper cutting machine. A spring 62 serves to 25 turn the trigger 58 to its normal position against a stop 63 after each operation by the roller 57.

The shaft 59 carries also an arm upon which a pawl 64 is pivotally mounted in a 30 manner to engage the peripheral teeth 65 of a supplemental counting wheel 65^a, mounted also upon the stud-shaft 42 and provided upon its face with a projection 66, the purpose of which will appear more fully hereinafter.

The pawl 64 may be maintained in proper engagement with the teeth 65 by means of a suitable spring 67, as shown in Fig. 2. Under certain conditions, which will be 40 more fully set forth further on in the description, the roller 57 is adapted also to actuate an auxiliary trigger 58^a located at a point diametrically opposite to the trigger 58 and mounted upon a shaft 59^a also journalled in the casing 10. The trigger 58^a carries a metallic contact member 60^a, similar to the member 60, and likewise arranged to engage and connect two electric terminals 61^a and thereby close a second electric circuit whereby a second alarm is operated at the proper time. A spring 62^a serves to return the auxiliary trigger 58^a to its normal position against a stop 63^a after each operation by the roller 57. The shaft 59^a carries also an arm upon which an auxiliary pawl 64^a is pivotally mounted in a manner to engage the teeth 65 of the supplemental counting wheel 65^a. In order that the auxiliary trigger 58^a and the auxiliary pawl 64^a may be rendered inoperative when use thereof is not desired, the pawl 64^a may be provided with an extension connected by means of a link 68 with a plunger 69 mounted in the casing 10 and controlled by a 55 spring 67^a; for the same purpose one of

the terminals 61^a is constructed in the form of a pivoted member connected at 70 with the link 68.

With this arrangement the spring 67^a will normally maintain the pawl 64^a in engagement with the teeth 65 and the movable terminal 61^a in a position to be engaged by the contact member 60^a. When use of the auxiliary pawl and trigger is not desired the plunger 69 is pressed inward against the tension of the spring 67^a and thereby, through the medium of the link 68, swings the pawl 64^a out of engagement with the teeth 65 and the movable terminal 61^a to an inoperative position out of reach of the contact member 60^a. When the parts are thus adjusted the operation of the trigger 58^a by the roller 57 will have no mechanical effect. Any suitable means may be provided for maintaining the parts in the described inoperative positions; for instance, a latch 71 pivoted at 72 in the casing 10 may be movable in front of the plunger 69 to prevent the spring 67^a from restoring the same to a position in which the trigger 58^a 90 and pawl 64^a are arranged to perform their functions. A lever 73 is fixed upon a rock shaft 74 journalled in the casing 10 and extends into the path of the projection 66, and at its free end is provided with a pivotally mounted pawl 75 adapted to engage the peripheral teeth 76 of an auxiliary counting wheel 77 also rotatably mounted upon the stud-shaft 42; a spring 78 serves to maintain the pawl 75 in engagement 100 with the teeth 76. In the illustrated example the counting wheel 65^a is provided with one hundred teeth, each of which indicates a ream of paper, and the counting wheel 77 has ten teeth 76, each indicating one thousand reams, as will be more fully brought out hereinafter. As shown in Fig. 2, spring-controlled stop pawls 46^a, 65^b and 76^a co-operate respectively with the teeth 46, 65 and 76 to prevent unintentional return movements of the group of wheels 45, 45^a, 45^b and 45^c and the wheels 65^a and 77 respectively.

In the preferred construction a disc 79 is secured upon the rock shaft 74 and is connected by means of a link 80 with an arm 81 pivotally supported upon the stud-shaft 20 and having a pawl 82 pivoted thereto at 83; the pawl co-operates with the teeth 84 of a counting wheel 85 and is maintained in operative engagement with said teeth by a spring 86. The counting wheel 85 is rotatably mounted upon the stud shaft 20 and registers the count totalled during a given period of time by the other counting members without regard to any adjustments of the latter which may have taken place during such period; in the present case, said counting wheel 85 represents a production dial whereby the production of 120

the machine with which the counting apparatus is combined is registered. To prevent unintentional return movement of the wheel 85, a stop-pawl 85^a pivoted at 85^b in the casing 10, may be provided, said stop-pawl being held in engagement with the teeth 81 by means of a spring 87.

In order to visibly indicate the count resulting from the operation of the counting wheel 85, the latter may be operatively combined with a pointer 88 arranged to move with the wheel 85 and co-operating with a scale or dial 89 located in registry with and visible through the glass 18 of the dial opening 12. The illustrated example shows the scale 89 provided with one hundred designations *c* each of which represents a unit of one hundred so that one complete revolution of the wheel 85 represents a grand total of ten thousand. In the preferred form the pointer 88 is arranged and combined with the mechanism in such a manner that it may be reset to zero only by an authorized person and accordingly may be provided with a suitable lock 90 whereby this result is attained.

The apparatus may further be provided with a pointer 91 connected to move with the supplemental counting wheel 65^a and co-operating with a scale or dial 92 located in front of the glass 18 of the dial opening 13; the scale 92 is provided with designations *d* reading counter-clockwise from zero to ninety-nine and each designating a unit which in the present instance corresponds to a ream of cut sheets. In order to permit the pointer 91 to be set to any desired point on the scale independently of the counting wheel 65^a the connection between the latter and said pointer is a flexible one which, in the present instance, is represented by a spring 93 which permits relative movement of the pointer 91 in one direction and carries it along in the opposite direction or operative movement of the wheel 65^a. Thus, the pointer 91 will partake of the movements of the counting wheel 65^a, but it may be independently adjusted to any one of the designations *d* without disturbing or actuating the counting wheel 65^a.

Another pointer 94 may be similarly connected by means of a spring 95 with the auxiliary counting wheel 77, and co-operates with designations *e* produced upon the dial 92 and also reading counter-clockwise from zero to nine hundred and ninety-nine, each designation *e* corresponding to a unit of one hundred. The setting of the pointer 94 is accomplished by first locking the pointers 91 and 94 together through the medium of plungers 96 which are normally held in inoperative positions by means of springs 97. When the plungers 96 are in the positions shown in Fig. 4, the two pointers 91, 94

reaches the predetermined designation *c* on the dial 92, whereupon the plungers 96 are permitted to resume their normal positions and the pointer 91 is independently adjusted to the predetermined designation *d* 70 on said dial 92.

In addition to their other functions, subsequently to be described, the pointers 91 and 94 are arranged to engage electric terminals 98 and 99 to close an electric circuit which serves, for instance, to automatically cause a stoppage of the cutting machine whereby the paper is being cut; the terminals 98 and 99 are located at the zero designations on the dial 92 and are engaged by the pointers 91 and 94 only when the latter are in registry with this position.

In practice, the counting apparatus is attached to the machine with which it operates, in the present instance a paper cutting machine, in any convenient manner and in proper position to enable the link 28 to be connected with the cutter in such a way that the rotation of the latter will cause a rocking movement of the arms 26^a and 26 and the shaft 27. For instance, as shown, the casing 10 may be provided upon its rear face with an undercut recess 100 adapted to fit upon a dove-tailed flange 101 located on the cutting machine at a convenient point, said casing 10 being fixed against unintentional removal from said flange in any conventional way; with the illustrated and described arrangement the counting apparatus may readily be connected with and removed from the cutting machine whenever, for any reason, this becomes necessary. At the same time it is possible to easily combine the counting apparatus with existing cutting or other machines.

To most clearly set forth the operation of the apparatus, it will first be assumed that single sheets of paper are to be cut, in which case a single web of paper may be fed from a roll through the cutting machine in the customary manner; it will be further assumed that these sheets are to be counted in reams comprising five hundred sheets each and that one lot consisting of two hundred such reams is required to fill an order. To automatically attain these results, the pointer 34 is set in registry with the first designation *a* from the zero mark on the scale 35 whereby the segment 33 is adjusted to a position in which the pawl 22 is permitted to engage successive teeth 21 of the primary counting member 19, as will appear more fully hereinafter; at the same time the pointer 51 is moved into registry with the designation five hundred on the scale 52 and thus sets the segment 48 in a position in which the roller 50 of the pawl 44 will travel in the recess 49 and permit said pawl to operatively engage the teeth 46 of the secondary counting member 45 at the 130

proper time, the other pawls 44^a, 44^b and 44^c being held in their inoperative positions out of engagement with the wheels 45^a, 45^b and 45^c. In addition, the pointer 94 is adjusted 5 counter-clockwise to a position in which it registers with the indication two hundred on the scale *e*.

As the cutting machine now operates, the pitman 28 will be reciprocated, by reason 10 of its connection with the rotary cutter of the paper cutting machine and will accordingly rock the arm 26^a, shaft 27 and arm 26; the latter, in turn, will transmit its motion to the link 25 and thereby cause the bell- 15 crank lever 24 to be similarly rocked and the pawl 22 to be correspondingly actuated. The arrangement is such that each time the rotary cutter performs its cutting action and, in the present instance, cuts one sheet 20 of paper, the operation of the parts will cause the pawl 22 to advance the counting member 19 one tooth. As the rotary cutter revolves to repeat its cutting operation, the parts referred to above will be caused to 25 partake of a movement of recovery during which the roller 32 will ride beneath and in engagement with the lower surface of the sector 33 and thus will maintain the pawl 22 out of engagement with the teeth 30 21. During this step the counting member 19 will be held against a return movement by means of the stop-pawl 29. When the machine is set for one sheet, as in the present instance, the adjustment of said sector 35 33 is such that the roller 32 will pass from beneath the same at the proper point to permit said pawl 22 to operatively engage each successive tooth 21 and thereby advance said counting member 19 in successive steps 40 corresponding to the distance between contiguous teeth 21. As the primary counting member 19 is provided with one hundred teeth 21, it follows that one complete revolution thereof means that one hundred 45 sheets have been cut by the cutter of the paper cutting machine. The step-by-step advance of the counting member 19 is partaken of by the rollers 38 and finally brings one of these rollers 38 into engagement with the roller 46 and, as the actuation of the member 19 continues, rocks the bell-crank lever 41 on the stud-shaft 42 and, through the medium of the pawl 44, advances the secondary counting member 16 one tooth. 50 This actuation of the bell-crank lever 41, pawl 44 and secondary counting member 45 occurs each time the primary counting member 19 has been advanced twenty teeth, or in other words, each time twenty sheets 55 have been cut; as the secondary counting member 45 is provided with twenty-five teeth 46 and as the rollers 38 are spaced apart a distance corresponding to twenty 60 of the teeth 21, it follows that one complete revolution of the primary counting member

19 indicating the cutting of one hundred sheets will advance the secondary counting member 45 a distance corresponding to five of its teeth 46. From this it will be obvious that five complete revolutions of the primary counting member 19, which result from the cutting of five hundred sheets, will bring about one complete revolution of the secondary counting member 45 and thereby indicate that one ream consisting of five 70 hundred sheets has been cut. At the completion of one full revolution of the secondary counting member 45, the roller 57 will engage the trigger 58 and pivotally swing the same to bring the contact member 60 into engagement with the terminals 61 whereby the electric circuit in which said terminals are located is closed and an alarm, either in the form of a light or a bell or both is actuated to announce the fact 75 that one ream of paper has been cut. With this arrangement it is impossible for the operator to unintentionally overlook the fact that the cutting of one ream has been accomplished. 80

At the same time, as the trigger 58 is actuated in the manner described, the pawl-carrying arm and the pawl 64 will be operated about the pivot 59 in a direction to advance the supplemental counting member 65^a one tooth and with it the pointer 91 which will move to the first designation *d* which lies to the right of the zero mark in Fig. 1. It will be understood that, primarily, the pointer 91 and scale *d* are intended for setting the mechanism to signal predetermined counts, as will be more fully pointed out hereinafter; at the same time, the pointer 91 and scale *d* may be utilized as counters by simply noting the number of 95 designations *d* to which said pointer has travelled from the zero mark. As the operation of the apparatus is continued and successive reams are counted in the indicated manner, the supplemental counting member 100 65^a will finally make one complete revolution, which brings the pointer 91 back to zero and corresponds to the completion of one hundred reams, as said member 65^a is provided with one hundred teeth 65. At 105 this stage the roller 66 will engage and rock the lever 73 and thus cause the pawl 75 to advance the auxiliary counting member 77 one tooth; the latter carries with it the pointer 94, which moves from the two hundred mark on the scale *e* to the one hundred mark thereon. This operation is repeated upon completion of another revolution by the counting member 65^a whereupon the pointer 94 is moved from the one hundred 110 designation on the scale *e* to the zero mark thereof. 115

This indicates that two hundred reams of five hundred sheets each have been cut. At 120 this stage the two pointers 91 and 94, being 125

- both in registry with the zero marks of the respective scales *d* and *e* are in engagement with the electric terminals 98 and 99 and thus complete an electric circuit which, as previously stated, may serve to automatically stop the cutting machine independent of any action by the attendant, so that no further sheets are cut. It will be understood that, if desired, the closing of the electric circuit by the pointers 91 and 94 may operate a signal to notify the operator of the completion of the predetermined lot, that is, in the present example, two hundred reams of five hundred sheets each. By adjusting the pointer 94 to other points on the scale *e*, say, for instance, five hundred, the cutting machine will be automatically stopped or the signal will be operated when a total of five hundred reams have been cut.
- If the particular order requires a number of reams less than a hundred, say fifty, the pointer 94 is set at zero and the pointer 91 is set at the fifty mark on the scale *d*; in this case both pointers will be in engagement with the electric terminals 98 and 99 when the pointer 91 reaches zero on the scale *d* or, in other words, when the counter 65^a has made a half revolution and fifty reams have been cut. If, on the other hand, the required lot is to consist of a number which is more than a hundred and includes a fraction of a hundred as, for instance, three hundred and eighty, the pointer 94 is adjusted to the three hundred point on the scale *e* and the pointer 91 is set at eighty on the scale *d*. In this case, the counting member 65^a, after making three complete revolutions and correspondingly actuating the counting member 77, in successive steps, to move the pointer from three hundred to two hundred and one hundred successively and finally to zero will make an additional partial revolution corresponding to eighty of its teeth 65 which brings the pointer 91 to zero and thereby closes the electric circuit through the terminals 98 and 99. During the three complete revolutions of the counting member 65^a the pointer 91 will engage the terminal 98 each time it reaches the zero point on the scale *d*, because of the fact, however, that during this time the pointer 94 has not yet reached the terminal 99, this periodic engagement of the terminal 98 by the pointer 91 has no effect. It is only when both pointers are coincidentally in engagement with both terminals 98 and 99 which, in the example given, occurs when three hundred and eighty reams have been cut, that the circuit will be closed.
- As the lever 73 and its co-related parts are operated by the roller 68 in the described manner, the disc 79, because it is fast upon the shaft 74, is also rocked, and by means of the link 80, swings the arm 81 on the stud-shaft 20 in a direction to cause the pawl 82 to advance the counting member 85 a distance of one of the teeth 84. In the illustrated example, this counting member 85 represents a production dial and is provided on its periphery with one hundred teeth 84; as said member 85 is advanced one tooth each time one hundred reams have been cut, it follows that one complete revolution of the member 85 will indicate the completion of ten thousand reams, any fraction of this total being correspondingly indicated by a partial rotation of said counting member 79. As the counting member 85 is operated in the described manner the pointer 88 will be carried along and will indicate on the scale *e* the actual number of reams which have been cut and thus serves to accurately register the total production of a given machine for a given period of time.
- If the reams to be cut are to consist of four hundred and eighty sheets instead of five hundred, the pointer 51 is shifted into registry with the indication four hundred and eighty on the scale 52, whereby the segment 48 is adjusted to a position in which the pawl 44^c is permitted to operatively engage the counting member 45^a and all of the other pawls are maintained in inoperative positions by the segment 48 owing to the fact that its recesses 49, 49^b and 49^c are out of registry with the rollers of the pawls 44, 44^b and 44^c while the recess 49^a is in registry with the roller of the pawl 44^a. As the counting member 45^a is provided with only twenty-four teeth 46 and is advanced one tooth for each twenty teeth 21 of the primary counting member 19, it follows that when the bell-crank lever 41 has been actuated twenty times, the counting member 45^a will have completed one revolution and thereby indicates that one ream, consisting of four hundred and eighty sheets, has been cut, twenty times twenty-four giving this total. The apparatus may similarly be set for counting reams of four hundred and three hundred and sixty sheets respectively, by adjusting the pointer 51 and segment 48 accordingly, it being understood that the operation of the mechanism is the same in principle in every case, and that an alarm is operated in each instance, at the proper time, through the medium of the roller 57, trigger 58, contact member 60, electric terminals 61 and the electric circuit closed thereby.
- Generally speaking, the cutting machine of which the rotary cutter constitutes a part is arranged to concurrently cut a plurality of sheets, in which case webs of paper, in the required number, are simultaneously fed through said cutting machine from rolls in the well known way. In such case, the successive units to be counted consist of the number of sheets which are cut at each operation of the cutter and which correspond

to the number of webs passing into the cutting machine; for instance, it may be assumed, for the purpose of illustration, that twenty sheets at a time are to be cut and 5 that accordingly twenty webs of paper are fed through the cutting machine. To provide for the proper co-operation of the counting apparatus under these conditions, the pointer 34 is set at the designation twenty 10 upon the scale 35, thus indicating that the counting mechanism is adjusted so that the primary counting member 19 will count in units of twenty. This is accomplished in the following manner: As the pointer 34 is 15 set upon the scale 35, the segment will be correspondingly adjusted and in the selected example, will be positioned in such a manner that the pawl 22 will be permitted to operatively engage each twentieth tooth and 20 at other times will be maintained out of engagement with said teeth. In other words, each advance of the primary counting member 19 will mean a forward step corresponding to twenty teeth or twenty sheets instead 25 of one tooth or one sheet, as in the example first described; the result set forth is obtained through the co-operation of the roller 32 with the segment 33 and by setting the latter at a point where the desired 30 engagement of the pawl 22 with the teeth 21 in the indicated manner is attained. In all other respects the operation of the counting mechanism is the same as previously described, it being understood that by adjusting the pointer 34 at any point on the scale 35, the segment will be set to cause 35 said primary counting member to advance or count in units corresponding to the number of sheets being simultaneously cut by the cutter 29.

If, for any reason, it should become necessary, when the machine is set, for instance, for twenty sheets, to discontinue the feeding of one or more webs of paper through the cutting machine, an accurate count may still be maintained by setting the pointer 34 to the designation *a* on the scale 35 corresponding with the number of webs or rolls of paper which are still being fed; that is to say, if two rolls of paper out of the twenty give trouble from any cause, these two are simply cut out and the pointer 34 is set to the designation eighteen on the scale 35, which brings about a corresponding adjustment of the segment 33. In this new position, the latter will permit the pawl 22 to engage each eighteenth tooth 21, so that the primary counting member 19 will be advanced eighteen teeth at a time or, in other words, will count in units of eighteen. If the difficulty with the two discontinued rolls is overcome and the same are again fed through the cutting machine, the counting apparatus may be again adjusted to count in units of twenty by setting the

pointer 34 back to the designation twenty on the scale 35; similarly, if the feed of additional webs of paper through the cutting machine is discontinued for any reason, the counting apparatus may be adjusted to operate in harmony by simply setting the pointer 34 at the proper point on the scale 35, which should always correspond with the number of sheets being cut at each operation of the cutter. Any and all of the 70 adjustments referred to may be made while the mechanism is in operation, thus avoiding the loss of time incidental to a stoppage of the machine.

At times, it may be desirable, in actual 80 practice to pass two parallel webs of paper through the cutting machine and to cut the same into sheets which are collected in individual stacks; that is, the cut sheets from one web will be stacked in one pile and the 85 cut sheets from the other web will be stacked in another pile. These sheets are counted by the apparatus, for instance in the following manner:

The segment 33 occupies the same position 90 as it does when single sheets are being counted, that is, with the pointer 34 in registry with the first designation *a* from zero on the scale 35, so that the pawl 22 advances the primary counting wheel 19 in successive 95 steps corresponding to one tooth 21. The auxiliary pawl 64^a on the other hand is permitted to assume an operative position, as shown in Fig. 2, by shifting the latch 71 from in front of the plunger 69. This 100 causes the spring 67^a to exert a push on said plunger which is transmitted in the form of a pull to the link 68 and swings the pawl 64^a into engagement with the teeth 65^a. At the same time, the movable terminal 61^a is adjusted to its operative position. Assuming that the production is to be in reams of five hundred sheets each, the segment 48 will be adjusted to a position in which the pawl 44 is in operative engagement with 110 the secondary counting member 45 and the other pawls are held in their inoperative positions; if the production is to be in reams consisting of four hundred and eighty, four hundred or three hundred and sixty sheets the segment 48 will be adjusted accordingly in the manner previously set forth.

If the cutting machine is now started the counting apparatus will operate in exactly 115 the same manner as previously described with respect to the cutting and counting of single sheets and the secondary counting member 45 will be periodically operated by the action of said pawl 44 through the medium of the bell-crank lever 41 and the rollers 38 of the primary counting member 19. This will finally bring the roller 57 into a position in which it swings the auxiliary trigger 58^a in a manner to engage the 120

contact member 60^a with both terminals 61^a whereby the electric circuit of which said terminals form a part, is closed and an alarm is operated. This step in the operation of the apparatus takes place when two hundred and fifty sheets have been cut from each web and stacked in each pile; in the preferred arrangement the operator now removes one of the stacks so that as the 19 operation of cutting continues a new stack will be started and at the same time the stacking of sheets will continue in the remaining original pile. As this goes on, the roller 57 will finally reach the trigger 58^a and operate the same to bring its contact member 60 into engagement with the terminals 61 whereby the electric circuit in which these terminals are located is closed and another alarm is operated. The parts are so 20 arranged and proportioned that this operation of the second alarm takes place after another unit of two hundred and fifty sheets has been cut. At this stage, therefore, the remaining original stack now consists of 25 five hundred sheets and accordingly is removed while the stack which succeeded the other original stack now comprises two hundred and fifty sheets. A continued operation of the apparatus will now continue to 30 add sheets to this stack of two hundred and fifty sheets and at the same time will commence the formation of a further stack. Thus, when the roller 57 again actuates the auxiliary trigger 58^a to operate the alarm 35 another stack of five hundred sheets will have been completed and at the same time two hundred and fifty sheets will have again been stacked in the other pile. This alternate completion of the piles in stacks of 40 five hundred sheets continues until the desired production has been reached.

As the triggers 58 and 58^a are alternately operated in the described manner, the pawls 64 and 64^a will be actuated to advance the 45 supplemental counting member 65^a whereby the counting wheel 85 is operated in the same way as previously described to register the production; in the same way the pointers 91 and 94 may be set and operate 50 in the manner hereinbefore set forth to engage the contact members 98 and 99 and close the electric circuit of which they 55 form a part and thereby bring about a stoppage of the cutting machine when the desired number of reams of five hundred sheets each has been completed.

Instead of feeding two single webs through the cutting machine in parallel relation to each other a plurality of webs may 60 be so fed, in which case the segment 33 is set accordingly by bringing the pointer 34 to the proper point on the scale 35. The operation of the mechanism will be the same, with this adjustment, as recited above.

85 The counting apparatus is novel and effi-

cient in operation and is capable if being readily and quickly combined with and disconnected from the machine with which it operates, and is particularly adapted for use in connection with paper cutting machinery. 70 The apparatus, in its illustrated form, not only accurately counts individual sheets but, in addition, automatically keeps track thereof, and in the preferred arrangement, gives visible or audible warning when a ream has 75 been completed regardless of the number of sheets contained in the ream. The apparatus further keeps an accurate tally of the number of reams and also maintains an accurate count of the production of a given 80 machine for a given period of time.

In the illustrated example the wheel 49 advances in periodical steps corresponding to different numerical units which always agree with the subject-matter of the count; 85 that is in the present instance, the number of webs of paper passing through the cutting machine or the number of sheets being cut thereby at each operation. Similarly the secondary counting wheels 45, 45^a, 45^b 90 and 45^c are advanced in steps corresponding to numerical units which are predetermined multiples of the numerical units of the primary counter. The same is true of the supplemental counting wheel 65^a and the 95 auxiliary counting wheel 77, each of which is advanced in steps corresponding to numerical units, each of which are multiples of the previously mentioned units; the counting wheel 85 is advanced in steps which 100 represent predetermined numerical totals of the counts by the entire counting mechanism and in the present example represents what may be termed a production dial to indicate the production of a given machine 105 in a given period of time.

While the counting apparatus is intended primarily for combination with a paper cutting machine, it may be used with equal efficiency with other types of machines, and it is, therefore, to be understood that the illustration and description, as herein incorporated, are not to be construed as defining the limits of the invention.

Various modifications in the specific form 110 shown and described may be made within the scope of the claims without departing from the spirit of my invention.

I claim:

1. A counting mechanism comprising a 120 plurality of counting elements movable in steps corresponding to different numeral units and means whereby any one of said elements may be selectively brought into action and the others at the same time 125 rendered inoperative in accordance with changes in the numerical units.

2. A counting apparatus comprising a plurality of counting members each representing a different count, a plurality of 130

actuating devices for operating said counting members and a setting device common to all of said devices whereby any one of them is adjusted to an operative position for actuating its co-operating member and the remainder of said devices are concurrently adjusted to inoperative positions. 5 member, a plurality of pawls carried by said means and each arranged to co-operate with one series of said teeth but not with the others, and adjustable means whereby one of said pawls are adjusted to an operative position and all of the others are maintained in inoperative positions. 70

3. A counting apparatus comprising a plurality of counting wheels each having a different number of teeth, a plurality of pawls for operating said counting wheels and a setting device common to all of said pawls whereby any one of them is adjusted to an operative position for actuating its co-operating wheel and the remainder of said pawls are concurrently adjusted to inoperative positions. 10 75

4. A counting apparatus comprising a primary counting member, means for operating said member in accordance with the subject matter of the count and a device whereby the operation of said means is selectively adjusted to actuate said counting member in variable steps corresponding to 20 different numerical units. 80

5. A counting apparatus comprising a primary counting member having a predetermined number of peripheral teeth, means, including a pawl, for operating said member in accordance with the subject-matter of the count, and a segment adapted to maintain said pawl in an inoperative position and to permit it to engage the teeth of said counting member at a predetermined point, 30 said segment being adjustable to vary said point of engagement whereby said counting member is actuated in steps corresponding to different numerical units. 85

6. A counting apparatus comprising a primary counting member having a predetermined number of peripheral teeth, means, including a pawl, for operating said member in accordance with the subject-matter of the count, a segment adapted to maintain 40 said pawl in an inoperative position and to permit it to engage the teeth of said counting member at a predetermined point, said segment being adjustable to vary said point of engagement whereby said counting member is actuated in steps corresponding to different numerical units, supplemental counting mechanism operated by said primary counting member, and adjustable means whereby said operative steps of said supplemental counting mechanism are made to correspond to different numerical units. 45 100

7. A counting apparatus comprising a primary counting member, means for operating said member in accordance with the subject-matter of the count, secondary counting mechanism including a plurality of series of teeth arranged adjacent to each other and each consisting of a different number of teeth representing different numerical totals, 50 means controlled by the primary counting 105

member, a plurality of pawls carried by said means and each arranged to co-operate with one series of said teeth but not with the others, and adjustable means whereby one of said pawls are adjusted to an operative position and all of the others are maintained in inoperative positions. 70

8. A counting apparatus comprising a primary counting member, means for operating said member in accordance with the subject-matter of the count, secondary counting mechanism including a plurality of series of teeth arranged adjacent to each other and each consisting of a different number of teeth representing different numerical totals, 75 means controlled by the primary counting member, a plurality of pawls carried by said means and each arranged to co-operate with one series of said teeth but not with the others, and an adjustable segment adapted to be engaged by said pawls and provided with recesses adapted to be individually brought into registry with said pawls whereby one of the latter is adjusted to an operative position and all of the others are 80 maintained in inoperative positions. 85

9. A counting apparatus comprising a primary counting member having a predetermined number of peripheral teeth, means, including a pawl, for operating said member in accordance with the subject-matter of the count, a segment adapted to maintain said pawl in an inoperative position and to permit it to engage the teeth of said counting member at a predetermined point, said segment being adjustable to vary said point of engagement whereby said counting member is actuated in steps corresponding to different numerical units, secondary counting mechanism including a plurality of series of teeth arranged adjacent to each other and each consisting of a different number of teeth representing different numerical totals, means controlled by the primary counting member, a plurality of pawls carried by said means and each arranged to co-operate with one series of teeth but not with the others, and an adjustable segment adapted to be engaged by said pawls and provided with recesses adapted to be individually brought into registry with said pawls whereby one of the latter is adjusted to an operative position and all of the others are 100 maintained in inoperative positions. 105

10. A counting apparatus comprising a primary counting member having a predetermined number of peripheral teeth, means, including a pawl, for operating said member in accordance with the subject-matter of the count, a segment adapted to maintain said pawl in an inoperative position and to permit it to engage the teeth of said counting member at a predetermined point, said segment being adjustable to vary said point of engagement whereby said counting member 110 115 120 125 130

- is actuated in steps corresponding to different numerical units, secondary counting mechanism including a plurality of series of teeth arranged adjacent to each other and each consisting of a different number of teeth representing different numerical totals, means controlled by the primary counting member, a plurality of pawls carried by said means and each arranged to cooperate with one series of teeth but not with the others, an adjustable segment adapted to be engaged by said pawls and provided with recesses adapted to be individually brought into registry with said pawls whereby one of the latter is adjusted to an operative position and all of the others are maintained in inoperative positions, and additional counting means arranged to be actuated through the medium of said secondary counting mechanism in steps corresponding to predetermined numerical totals.
11. A counting apparatus comprising a casing adapted to be mounted upon a paper cutting machine, a primary counting wheel in said casing provided with a predetermined number of peripheral teeth, a pawl co-operating with said teeth, a bell-crank

lever carrying said pawl, means adapted for connection with the paper cutting machine for operating said bell-crank lever in co-ordination with the cutter of said paper cutting machine, an adjustable segment adapted to maintain said pawl in an inoperative position and to permit it to engage said teeth at a predetermined point whereby said primary counting wheel is advanced in steps corresponding to predetermined numerical units predetermined by the number of sheets being cut by said cutting machine, a plurality of projections located at spaced intervals upon said primary counting member, a bell-crank lever arranged to be periodically actuated by said projections, supplemental counting mechanism operated by said lever, additional counting mechanism for registering production in predetermined numerical units, and means controlled by said supplemental counting mechanism for operating said additional counting mechanism.

In testimony whereof I have hereunto set my hand.

LOUIS LA VECK
